Patented Apr. 29, 1958

182,701

FISHING REEL

Morris E. Wood, Bronson, Mich., assignor to Higbie Manufacturing Company, Rochester, Mich., a corporation of Michigan

Application August 21, 1956, Serial No. 42,676

Term of patent 14 years

(Cl. D31—4)

I claim:

The ornamental design for a fishing reel, as shown.
